UNITED STATES PATENT OFFICE.

HERMAN G. LARZELERE, OF NEW ROCHELLE, NEW YORK.

CONCRETE-MOLD.

1,313,393.

Specification of Letters Patent.

Patented Aug. 19, 1919.

Application filed December 18, 1918. Serial No. 267,272.

To all whom it may concern:

Be it known that I, HERMAN GRANT LARZELERE, a citizen of the United States, and a resident of New Rochelle, in the county of 5 Westchester and State of New York, have invented certain new and useful Improvements in Concrete-Molds, of which the following is a specification.

My invention relates to improvements in 10 forms for molding concrete walls and the like, and it consists in the constructions, combinations, and arrangements herein described and claimed.

An object of my invention is to provide 15 a form for molding concrete structures, consisting of sectional standards and form plates that can be built up to any desired height with comparative ease, one of the outstanding features being the relative 20 lightness of the parts whereby they can be handled by the workmen.

Another and important object of the invention consists in providing an exposed portion on each of the wooden standards 25 and on the inside of the form, so that reinforcing rods and metal of various kinds can be temporarily nailed in place, said exposed portions being formed by rabbeting the inner vertical edges of the standards to 30 make recesses for the reception of parts of the form plates.

A further object of the invention is to provide a novel tie wire tightening mechanism.

35 A further object of the invention is to provide wooden battens to be laid between superposed form plates to make tight compression joints and prevent fluid cement from leaking.

40 Other objects and advantages will appear in the following specification, reference being had to the accompanying drawings in which:—

Figure 1 is a side elevation showing a wall 45 form partly set up,

Fig. 2 is a longitudinal section of a wall taken through a corner,

Fig. 3 is a horizontal section substantially on the line 3—3 of Fig. 1,

50 Fig. 4 is a perspective view of one of the tie wire tighteners,

Fig. 5 is a detail perspective view showing the wooden batten between abutting or superposed form plates, and

55 Fig. 6 is a detail perspective view illustrating the use of wooden cleats to brace

the form plates, instead of the metallic angles shown in Fig. 1.

In carrying out my invention, a plurality of metal sockets 1 are nailed at evenly spaced intervals to wooden shoes 2, by driving the nails through the holes 3 in the flanges 4 of the sockets. The wooden shoes 2 may consist simply of scantlings that are laid upon the ground substantially as shown in Fig. 2. These shoes form no part of the wall and are removed after the concrete hardens so that the improved form can be taken away.

A plurality of wooden posts 5 are fitted in the respective sockets as shown in Fig. 1. In building up the form for the wall, other posts are added and joined by couplings 6. The standards of the form are thus made.

The posts 5 are reduced at 7 at the lower ends to fit in the sockets 1. A plain bolt 8 is passed through each socket and the end of the post seated therein, and the bolt is secured by a pin 9. Vertical rabbets 10 on the inner edges of each post, provide recesses or seats for the channel portions 11 of the form plates, and an interiorly exposed wooden section 12 to which parts of the reinforcing iron 13 are nailed.

The channel portions 11 have nail holes 14 through which nails are driven into the post 5 to secure the channels in place. Parts of the horizontal angles 15 that brace the form plates 16, are cut away to enable the angles to be evenly fitted against the channels 11 as shown in Fig. 3. In applying the form plates 16, rivets or equivalent securing means are used. The parts of the form plates that overlap the channels 11, serve to bind the two together and make a rigid structure.

Wires 17 are used as auxiliary means to secure the form plates to the posts. These wires are knotted at the holes in the angles adjacent to the posts. Tie wires 18 keep the standards from leaning outwardly under the influence of the pressure on the inside. One end of each of these wires is threaded through an opening 19 in either the outside or the inside post, and is then wrapped around a pin 20.

Bearing plates 20 support the pin. A lock pin 21 is fitted through any pair of properly alining apertures in the plate 20 at the right and the flange 22 of the pin

20. A square head 23 on the pin enables it to be turned to forcibly wrap the end of the wire 18, and thus the tie wire is tightened with only a remote possibility of 5 breaking it. A shallow groove 24 in the post, behind the pin, makes room for the wire thereon. It is to be observed that a slot 25 in the winding pin enables the end of the wire to be held.

10. Wooden battens 26 are inserted between abutting angles 15^a of superposed form plates to make tight compression joints. Grooves 27 are formed in each batten at 15 the base of the exposed head, to leave a space beneath the horizontal parts of the angles 15^a and the batten. Any leaking cement will run into these grooves or spaces, quickly fill them and prevent further leakage from the wall. Holes 28 arranged at 20 any desired intervals, are used where additional tie wires are needed to keep the wall forms from buckling.

As an alternative measure, the wooden battens just described may be omitted and 25 the abutting angles 15^a drawn together into tight contact by threading short pieces of wire through alining holes 15^b. Instead of employing metal angles 15 to stiffen the form plates, wooden cleats 29 as in Fig. 6 30 may be used. Fig. 6 also shows how the form plates 16 may consist of wood instead of metal. It may be desirable under certain circumstances to use wood instead of metal, and the purpose of Fig. 6 is therefore to 35 illustrate the employment of this material as well as the battens to brace the plates. In the use of either, the form plates are comparatively light and it may be readily handled by the workmen without the aid of 40 machinery to lift them.

Briefly summing up the important features of the invention, the provision of the exposed wooden section 12 of each post is a great advantage in affixing the reinforcing rods. After the wall hardens the posts 45 can be readily torn away, leaving the nails which can be cut off.

The provision of wooden battens between vertically superposed form plates makes for 50 a tight joint. The mold is caused to bear tightly at the joint of greatest resistance. The improved tightening arrangement for the tie wires, makes it easy to tighten the wires 18, at the same time avoiding the common danger of breaking these wires by 55 excessive twisting.

While the construction and arrangement of the concrete mold is that of a generally preferred form, obviously modifications and 60 changes may be made without departing from the spirit of the invention or the scope of the claims.

I claim:—

1. In a concrete mold, a post having rabbets on the inner vertical edges, to provide

recesses and leave an exposed section to which reinforcing irons can be secured from the inside.

2. A concrete mold, comprising a post having rabbets on the inner vertical edges, 70 to provide recesses and leave an exposed section to which reinforcing irons can be secured from the inside of the mold, form plates fitted against the exposed section and making a flush surface on the inside, and 75 channels fitted in the recesses and carrying the form plates.

3. A concrete mold, comprising a post having rabbets on the inner vertical edges, 80 to provide recesses and leave an exposed section to which reinforcing irons can be secured from the inside of the mold, form plates fitted against the exposed section and making a flush surface on the inside, channels fitted in the recesses and carrying the 85 form plates, and means for securing the form plates to the post, including nails driven through the channels into the post.

4. In a concrete mold, a post having an inward opening, a winding pin with an 90 opening, located in front of the post opening to receive one end of a tie wire threaded through said opening, means providing bearing supports for the winding pin, one of said means having holes, a flange on the 95 winding pin with holes arranged to aline with the aforesaid holes, a non-circular turning head on the pin, and a lock pin to be fitted in alining holes to retain the winding pin when turned the desired amount. 100

5. In a concrete mold, the combination of a pair of vertically superposed form plates having abutting angle irons on the edges, and an insertible batten to make a tight joint between the form plates, said batten 105 including an exposed head and having grooves at the base of the head to provide longitudinal spaces to receive leaking fluid and prevent further leakage when the spaces are filled. 110

6. A concrete mold comprising shoes laid on the ground, sockets attached to the shoes at equal intervals, posts having reduced ends fitted into the sockets, means for securing the posts in the sockets, said posts having 115 rabbets on the inner vertical edges to provide recesses and interiorly exposed nailing sections, a winding pin supported transversely of each post and arranged to receive one end of a cross tie wire, means embodied in said pin enabling it to be turned and locked to various adjustments, a plurality of form plates with channels arranged to be secured between the posts in the recesses and making flush surfaces with 120 said nailing sections on the inside; horizontal bracing means for the form plates including angle irons on abutting edges, and insertible battens securable between said 125 abutting angle irons to make tight com- 130

pression joints and prevent the leakage of fluid from the inside.

7. A concrete mold, including a form post with vertical recesses arranged to leave an exposed nailing area on the inside of the mold, and form plates with strengthening means fitting into the recesses and adapted to be secured to adjacent parts of the post.
- 10 8. A concrete mold, including form plates with horizontal strengthening means including members at the edges arranged to be secured together and tie vertically superposed plates in erecting the mold, vertically disposed strengthening means on the vertical edges, and a form post with recesses ar-

ranged to leave an exposed nailing area on the inside of the mold, said recesses receiving the vertical strengthening means.

9. A concrete mold, including a pair of 20 spaced form posts provided with opposed recesses leaving exposed nailing areas on the inside of the mold, form plates including reinforcing members arranged to occupy the recesses and obtain a flush surface on the 25 inside, suitable means for securing said form plates to each of the form posts, and adjustable means mounted on one of the posts for creating tension in a tie wire anchored in the other post and extending to 30 said adjusting means.

HERMAN G. LARZELERE.
